UNITED STATES PATENT OFFICE.

SAMUEL K. DENNIS, OF CHICAGO, ILLINOIS, ASSIGNOR, BY MESNE ASSIGNMENTS, TO INTERNATIONAL HARVESTER COMPANY, A CORPORATION OF NEW JERSEY.

CULTIVATOR.

1,382,764.

Specification of Letters Patent. Patented June 28, 1921.

Application filed March 20, 1916. Serial No. 85,355.

To all whom it may concern:

Be it known that I, SAMUEL K. DENNIS, a citizen of the United States, residing at Chicago, in the county of Cook and State 5 of Illinois, have invented certain new and useful Improvements in Cultivators, of which the following is a full, clear, and exact specification.

This invention relates to cultivators, and 10 particularly two-row cultivators.

One of the objects of this invention is to simplify, lighten and improve cultivators of the two-row type.

Another object is to improve the control 15 and adjustable features of cultivators.

A further object is to provide a two-row cultivator, compact and durable, which is adapted to meet all the requirements for successful commercial operation.

20 These and other objects are accomplished by providing a cultivator having gangs connected to swinging bail members and supported by the frame in a manner to be pushed, as distinguished from being drawn, 25 and having improved means for controlling the raising, lowering and lateral movements of the cultivator gangs, and improved means for steering the cultivator.

This invention is illustrated on the accompanying sheets of drawings, in which—

30 Figure 1 is a fragmentary top plan view of a two-row cultivator embodying my invention;

Fig. 2 is a side elevation of the same, 35 parts being broken away and in section;

Fig. 3 is a detail view showing the method of supporting the wheel carrying steering axle mounted at the sides of the main frame;

40 Fig. 4 is a detail section through the rear member of the main frame, showing the main segment used in locking the cultivator gangs in various raised and lowered positions;

45 Fig. 5 is a fragmentary front view of means for controlling the lateral swinging movements of the individual gangs;

Fig. 6 is a fragmentary sectional view of the same on line 6—6 of Fig. 5;

50 Fig. 7 is a detail side elevation of the foot lever mechanism for angling the wheels;

Fig. 8 is a fragmentary rear view of the same;

55 Fig. 9 is a fragmentary detail view of the front portion of the steering mechanism.

The various novel features of my invention will be apparent from the following description and drawings and will be particularly pointed out in the appended claims.

The frame of this two-row cultivator includes a main transversely arranged member 10 located at the rear and preferably of inverted U-section, as best seen in Fig.

60 4, and a parallelly arranged, transversely extending frame member 11 located in advance of the main frame member 10, and which is preferably made of angle material.

The frame members 10 and 11 are connected by two pairs of forwardly converging brace members 12 and 13, which terminate in parallel portions to receive draft tongues 14,

65 the rear ends of which are secured to the cross front frame member 11. Secured to

70 the opposite ends of the main frame member 10 are brackets 15 (see Fig. 3) having upper portions secured within the ends of the U-shaped member 10 and provided with upper and lower bearings 16 and 17, respec-

75 tively, to receive vertical portions 18 of the axles or spindles 19 carrying traction wheels

80 20. Extending upwardly and forwardly of ear members 21 on bearing members 17 (see Fig. 2) are braces 22, which are secured to

85 the outer brace members 12 and 13 just below the forward frame member 11. It is to be noted at this point that the wheel carrying spindles have integrally formed with

80 the portions 19 and 18 a forwardly and downwardly extending hook portion 23

90 which terminates in a horizontal portion 24, to which is pivoted a casting 25 detachably mounted upon one end of a connecting motion-transmitting member 26. It is to be

95 understood that the members 23 are located on both sides of the machine and that the member 26 connects them for transmitting a simultaneous steering motion to the traction wheels 20.

For changing the angularity of the steering wheels for steering purposes, the following control arrangement is provided:

To the under side of the middle portion of the front frame member 11 is pivotally connected a T-shaped lever member 27, the stem 28 of which extends rearwardly and

105 downwardly and terminates in a slotted portion 29 for the reception of a pin 30 on a bracket member 26' which is sleeved on member 26 and held in any adjusted position

110

by a set screw 31. The stem 28 of the T-shaped member is prevented from falling out of engagement with the pin 30 by a cotter 32. Pivots secured to the ends 5 of the oppositely extending arms 33 and 34 of the T-shaped member 27 are rearwardly extending links 35 and 36, respectively which are pivotally connected to foot levers 37 and 38, respectively, provided with foot 10 treadles 39 and 40. The front ends of the foot levers 37 and 38 are pivotally supported by a suitable bracket 41 secured to the central portion of the main frame member 10. By means of this arrangement it is apparent 15 that the foot levers 37 and 38 can be actuated from the operator's seat 42 to shift bar 26 laterally and thereby angle the traction wheels 20 simultaneously for changing the path of the cultivator. The seat 42 is adjustably secured by a bolt 43 to seat-supporting bars 44 which pass over and rest upon the main frame member 10 and are pivotally connected to the inner members of the braces 12 and 13.

25 The cultivator gangs 45, 46, 47 and 48, which may be of any suitable type, are individually supported at their front ends by bail members 49, the upper horizontal portions of which are loosely journaled and 30 movable longitudinally to some extent in suitable bearings 50 mounted on or formed in the frame members 10 and 11, the front portions of the bail members extending downwardly and slightly forwardly and terminating in loops or eyes 80¹ which loosely receive projections 51 extending forwardly from the main portion of members 52 which also have trunnions extending into bearing portions 53 of the front ends of side bars of 35 each gang. In this way the gang members may swing laterally about the horizontal axis of the bail 49 and swing on the trunnions during raising and lowering movements of the gangs. The rear end of each 40 bail member extends downwardly through a slotted member 54 between the side bars of each gang. The front of each gang also is yieldingly supported by suitable springs 55 connected to eye bolts 56 which pass 45 through the front frame member 11 and adjusted by suitable members 57 for changing the effect of the springs 55. It will be noted that the gangs in this case are not pulled in the same sense that gang members of 50 other cultivators are, for the reason that push rods 58 are provided, the upper ends of which are pivotally mounted in bearings 59 secured to the rear of the frame member 10, and the front portions of which are slidably journaled in bearing portions 60 of members 52. By this arrangement the rods 58 transmit a pushing or thrusting action from the main frame member 10 to the front ends of each of the gang members.

65 It will be noted that the bearing portions

60 are made free to slide up and down on the vertical ends of the push rods 58, thereby permitting these elements to swing about the horizontal axes of the bails 49. It is necessary, moreover, to accommodate the 70 forward and backward motion of the members 52 due to the fact that they swing about the rear end of the push rods 58 in the bearings 59. This is accomplished by permitting the bails 49 to slide endwise in the bearings 75 50. The bails 49 and the members 52 of the gangs 45 therefore move backward and forward together enough to compensate for the swing of the push rod 58. It will also be noted that the upper and lower ends of the 80 push rods 58 are parallel to each other and connected by the portion therebetween, a crank member being formed which permits of the lateral movement of the gangs to a degree meeting practical requirements without any cramping action being occasioned, while the bails 49 serve to keep the beams at right angles to the frame during lateral adjustment and parallel to each other at all times.

90 Mention has been made of the fact that the gangs may be moved laterally. This is for the purpose of changing the distances between the gangs. Slidably mounted upon the connecting member 26 are sleeve members 61 having depending arms 62 (see Figs. 5 and 6), to which are secured rods 63 which extend downwardly through apertured plates 64 secured to side bars of the cultivator gangs. By means of this arrangement it is seen that if the sleeve members 61 are shifted laterally on the connecting member 26, the gangs will be moved and adjusted laterally with respect to each other. The gangs may be locked in their adjusted 95 position by suitable locking members 65 which pass into slots 66 (see Fig. 1) properly located in a cross bar 67 secured to the bracket 26¹ which carries pin 30. The slotted bar 67 is supported further by looped portions 68 formed integral with the sleeve members 61.

100 The cultivator gangs may be raised and lowered individually or simultaneously by means of the following control mechanism: 115 As shown, this cultivator is provided with four gangs. Two sets of levers of three each are provided for controlling the raising and lowering movement of the gangs. One set will be described in detail, it being understood 120 that the other set is substantially the same except for right and left-hand parts. Mounted upon the main frame member 10 and to one side of the middle thereof, are suitable supports for a stationary rod 69, 125 about which the lever members 70, 71 and 72 may pivot. The lever member 70 is provided with an elongated sleeve portion 72¹ which surrounds one portion of the rod 69 and terminates in an arm 73, which is flexibly 130

connected with the cultivator gang 45 through a rod 74 and spring 75. The lever 71 has at its lower end a small sleeve portion 76 which also surrounds the rod 69 and 5 has an arm 77 which is operatively connected to the gang 46 in a similar manner. From this arrangement it is seen that if the lever 70 is actuated, the gang 45 may be raised and lowered, and if the lever 71 is 10 actuated, the gang 46 may be raised and lowered. It will be noted that the central lever 72 is provided with and carries oppositely extending segment members 78 and 79, the first of which normally is engaged 15 by the detent 80 of lever 70 and the second of which normally is engaged by the detent 81 of the lever 71. The central lever 72 also has a detent 82 which normally engages with a main segment 83 secured to the frame 20 member 10. By raising the detent 80 the side lever 70 is released from the central lever and may be actuated for raising and lowering the gang 45 individually. In a like manner, if the detent 81 of lever 71 25 is raised, said lever will be released from the central lever 72 so that the gang 46 may be raised and lowered individually. However, if it is desired to raise and lower two gangs 45 and 46 simultaneously, levers 70 30 and 71 will remain locked to their respective segments 78 and 79 of the central lever 72 and said central lever 72, after being liberated from its segment 83, may be actuated for raising and lowering the gangs 45 and 35 46 simultaneously. In a like manner, the gangs 47 and 48 are individually and simultaneously raised and lowered.

In operation, the desired spacing of the gangs is obtained by adjusting the sleeve 40 members 61 on bar 26, their connections to the gangs through rods 63 and plates 64 causing each gang to move laterally with its sleeve member 61, the loose connections of the gangs to bails 49 and of the bails to the 45 frame permitting a sufficient range of movement to meet all requirements while keeping the gangs in parallel relation at all times. Lateral adjustment of the gangs, of course, necessitates proper setting of the individual 50 lifting levers to properly level each gang as the links 74 form one of the supports of the gangs. With the gangs in desired positions and the cultivator in use, guiding of the cultivator to follow deviations in the 55 rows is effected through the lever mechanism 28-39 above described which operates to shift bar 26 laterally on the machine and with it the gangs, at the same time angling the wheels to steer the machine in the direction of the shift. Such deviations are never great, and only a slight movement of the gangs and wheels is required to follow them, the combined actions of shifting and steering resulting in considerable lateral 60 movement of the gangs relatively to the rows 65

owing to the fact that the gangs are swung laterally on the frame while the frame is being steered laterally in the same direction.

This two-row cultivator is simple, light, durable, relatively inexpensive, and has a 70 great range of adjustment, together with control features including the steering of the cultivator, the lateral swinging adjustment of the gangs, and the individual and simultaneous raising and lowering feature of the 75 gangs, which together provide a cultivator which is adapted to meet the many requirements for successful operation.

It is evident that there may be various 80 modifications of the arrangement herein particularly described, and it is my intention to cover all such modifications which do not involve a departure from the spirit and scope of my invention as set forth in the following claims:

What I claim as my invention and desire to secure by Letters Patent is:

1. In a cultivator, the combination of a frame, swiveled wheels thereon, a steering bar connecting the wheels, forwardly and downwardly extending push rods pivoted to the frame on vertical axes, implement beams pivoted on the lower ends of said rods, latch members slidably mounted on said steering bar and provided with depending arms 90 loosely engaged with the beams, and latch locking means on said connecting bar positioned for engagement by said latch members.

2. In a cultivator, the combination of a 100 frame, swiveled wheels thereon, a steering bar connecting the wheels, forwardly and downwardly extending push rods pivoted to the frame on vertical axes, implement beams pivoted on the lower ends of said rods, laterally swinging bails having their horizontal portions loosely journaled on the frame and their arms loosely engaged with the beams, latch members slidably mounted on said steering bar and provided with depending arms 105 loosely engaged with the beams, and latch locking means on said connecting bar positioned for engagement by said latch members.

3. In a cultivator, the combination of a 115 frame, swiveled wheels thereon, a steering bar connecting the wheels, forwardly and downwardly extending push rods pivoted to the frame on vertical axes, implement beams pivoted on the lower ends of said rods, latch members slidably mounted on said steering bar and provided with depending arms loosely engaged with the beams, latch locking means on said connecting bar positioned for engagement by said latch member, and means for shifting the connecting bar laterally thereby simultaneously swiveling 120 the wheels and shifting the gangs.

4. In a cultivator, the combination of a 130 frame, swiveled wheels thereon, a steering

bar connecting the wheels, implement beams connected to the frame for lateral movement, latch members slidably mounted on said steering bar and provided with depending 5 arms loosely engaged with the beams, a latch bar secured to said steering bar and slidably engaged by each of the latch members and means for adjustably locking the latch members to the latch bar for laterally 10 adjusting the beams.

5. In a cultivator, the combination of a wheel supported frame including a main transverse member, a forwardly and downwardly extending push rod pivoted to the 15 frame on the vertical axis, an implement beam pivoted to the lower end of the push rod on a vertical axis, means for shifting the beam and push rod laterally, and a laterally swinging member comprising a horizontal portion loosely journaled on the frame 20 a forward arm loosely engaged with the forward end of the implement beam in advance of the push rod and a rear arm loosely engaged with a rear portion of the beam, said 25 swinging member maintaining the beam at right angles to said main frame member when the beam is shifted laterally with the push rod.

6. In a cultivator, the combination of a wheel supported frame including a main 30 transverse member, a forwardly and downwardly extending push rod pivoted to the frame on a vertical axis, an implement beam pivoted to the lower end of the push rod on a vertical axis, means for shifting the beam 35 and push rod laterally, and means for keeping the beam at right angles to said main frame member when the beam is shifted laterally with the push rod.

7. In a cultivator, the combination of a 40 wheel supported frame including a main transverse member, a forwardly and downwardly extending push rod having vertically positioned upper and lower ends, the upper end being journaled in a vertical sleeve on 45 the frame, an implement beam having a sleeve member journaled on the lower end of the push rod and movable vertically thereon, a suspension spring connecting the front end of the beam with the frame, and a bail member loosely journaled on the frame and having its arms engaged with the front end and intermediate position of the beam respectively.

In testimony whereof I affix my signature. 55
SAMUEL K. DENNIS.
